OARLOCK

Lawrence E. Slavin, Homer, Territory of Alaska

Application February 19, 1948, Serial No. 9,440

3 Claims. (Cl. 9—26)

1

This invention relates to new and useful improvements and structural refinements in oar locks for row boats, and the like, and the principal object of the invention is to facilitate retraction of the oar locks below the gunwale of the boat when not required, so that they do not protrude and interfere while the boat is being docked.

This object is achieved by the provision of an oar lock assembly which is securable to the gunwale of the boat and includes an oar receiving socket swingable from an upwardly projected position to a retracted position below the gunwale, as will be hereinafter more fully described.

An important feature of the invention resides in the provision of an oar lock which is simple in construction, which may be quickly, easily and conveniently manipulated, and which will not readily become damaged.

Another feature of the invention resides in the provision of an oar lock which will readily lend itself to economical manufacture and which is otherwise well adapted for the purpose for which it is intended.

With the above more important objects and features in view and such other objects and features as may become apparent as this proceeds, the invention consists essentially of the arrangement and construction of parts as illustrated in the accompanying drawings, in which:

Figure 1 is a perspective view of the invention, showing the same in situ on the gunwale portion of a boat;

Figure 2 is a longitudinal cross sectional view of the invention per se, and

Figure 3 is a cross sectional view, taken substantially in the plane of the line 3—3 in Figure 2.

Like characters of reference are employed to designate like parts in the specification and throughout the several views.

Referring now to the accompanying drawings in detail, the invention consists of an oar lock designated generally by the reference character 10, the same embodying in its construction a horizontally elongated housing 12 including a pair of spaced side plates 14 secured by bolts 16 to a pair of end blocks 18.

These end blocks may, if desired, be provided at their upper ends with outwardly angulated ears 20, through which suitable bolts or screws 22 may be passed for the purposes of securing the entire oar lock to the ribs 24 of the boat hull 26, adjacent the gunwale 28.

A transversely extending pin 30 is secured in the side plates 14 of the housing 12 and a disk 32, provided with a circumferential flange 34, is

5 pivotally mounted on the pin 30, one of the aforementioned end blocks 18 being recessed, if desired as indicated at 36, to facilitate pivotal movement of the disk by providing clearance for the flange 34 thereof, as will be clearly apparent.

10 The flange 34 of the disk 32 is formed integrally with a cam-surfaced portion or protuberance 38, while a coacting cam-surfaced portion 40 is formed integrally with an oar-receiving socket 42 of more-or-less conventional type. The cam-surfaced portion 40 of the socket 42 is, in turn, provided with a screw threaded shank 44 which extends rotatably through the flange 34 of the disk 32, carrying at its inner end portion a compression spring 46 and an adjusting nut 48.

15 The spring 46 urges the cam-surfaced portions 38, 40 in frictional engagement, and the cam-surfaces of these two portions are so configured that the socket 42 is thereby urged to be normally disposed in the plane of the disk 32. That is to say, the socket 42 is normally disposed in the plane of the disk 32, but the socket may oscillate, so to speak, about the axis of the shank 44 with the movement of the oar.

20 The socket 42 is swingable from its upwardly projected position to a retracted position below the gunwale 28, as shown by the phantom lines 50. This is facilitated by the pivotal movement of the disk 32 on the pin 30, the cam-surfaced portions 38, 40 assuring that the socket 42 is normally disposed in the plane of the disk 32, so that it may recede to its retracted position (50) in the housing 12. Means are provided for urging the socket into its retracted position, said means comprising a spiral spring 52, one end of which is anchored in a slot 54 provided in the flange 34 of the disk 32, while the remaining end of the spring is similarly anchored in a slot 56 formed in the pin 30. It is to be noted that the spring 52 is wound in such manner as to urge the socket 42 to its retracted position, illustrated at 50.

25 The flange 34 of the disk 32 is provided with a notch 58 and with an outwardly projecting lug 60, the latter being engageable with one of the aforementioned end blocks 18 and thereby retaining the socket 42 in a substantially upright position, as shown in the accompanying drawings. That is to say, the lug 60 prevents the socket 42 from swinging in a clockwise direction beyond its upright position, and releasable means are also provided for preventing the socket from swinging in an anti-clockwise direction to its retracted position shown at 50.

These last mentioned means include a trigger 62 pivoted upon a pin 64 mounted in the housing 12, a spiral spring 66, mounted upon a further pin 68 in the housing, urging an end portion of the trigger 62 against the flange 34 of the disk 32 and in engagement with the aforementioned notch 58 when the socket 42 is in its upright position.

Accordingly, when the invention is placed in use, the socket 42 is upwardly projected, in which position it is retained by the engagement of the lug 60 with one of the end blocks 18, and by the engagement of the trigger 62 with the notch 58, as is best shown in Figure 2.

However, when the oar lock is not required, the trigger 62 is disengaged from the notch 58, thereby permitting the spring 52 to rotate the disk 32 on the pin 30, so that the socket 42 is brought to its retracted position within the housing 12, as indicated at 50.

Needless to say, the socket may be projected for subsequent use by simply withdrawing it from the housing 12 against the resiliency of the spring 52, until the trigger 62 again engages the notch 58. A suitable finger piece 70 may be provided on the socket, to facilitate its withdrawal.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction and arrangement of parts may be resorted to without departing from the spirit and scope of the invention as claimed.

Having described the invention, what is claimed as new is:

1. An oar lock comprising a pair of spaced side plates forming a housing attachable to the gunwale of a boat, a pin mounted in said side plates, a flanged disc pivoted on said pin, an oar-receiving socket pivoted to the flange of said disc, a spiral spring anchored to said disc and to

said pin for swinging said socket from an upwardly projected to a retracted position in said housing, the flange of said disc being formed with a notch, and a spring-pressed trigger pivoted to said housing, said trigger being engageable with said notch when said socket is in its projected position.

2. The device as defined in claim 1, together with means for urging said socket in a predetermined relative position with respect to said disc, said means comprising a cam-surfaced portion on said socket, a coacting cam-surfaced portion on the flange of said disc, and a compression spring for urging said portions together.

3. In an oar lock, the combination of a housing adapted to be attached to the gunwale of a boat, a pin extending transversely in said housing, an oar socket supporting member rotatably mounted on said pin, an oar socket pivoted to said member for swinging movement about an axis perpendicular to the axis of the pin, said member being rotatable from a position wherein said socket projects upwardly from said housing to a position wherein the socket is retracted in the housing, resilient means for rotating said member and said socket to the retracted position, means for locking the member and the socket in the projected position, and additional means for swinging said socket on said member to a position wherein it is substantially parallel to the plane of rotation of said member.
